Application October 4, 1937, Serial No. 167,149

5 Claims. (Cl. 72—18)

This invention relates to a multiple brick unit. It has particularly to do with the design of a brick facing for use in brick facing or veneer sheets and multiple brick or tile units for the veneering or facing of interior or exterior walls of buildings. The invention further relates to the design of insulation sheet to receive brick facings.

One of the problems in the forming of a brick facing wall has been to obtain a completed wall which shows an unbroken bond without continuous vertical joints of more than one course high which would indicate that the wall is composed of a number of smaller multiple brick units. Where two or more horizontal layers of brick 10 form the unit, or where in a multiple sheet more than one brick course is formed on the sheet, the end design of the multiple units has been an irregular design adapted to fit or interconnect with adjacent units to prevent the showing of 20 the joints between the units. This design has been either the so-called "prong" design where every other end brick projects part of a length beyond the end of the unit, or the "step up" design where the multiple brick unit is substantially triangular in shape, the sloping sides being staggered or stepped up. These designs for multiple brick units have proved unsatisfactory since the irregular ends are subject to breakage in handling and shipping, and the cost of manufacture is higher and application more difficult than if the unit had a square abutting edge. One means of avoiding the irregular edge has been by making a special design which, although making a square end unit, does not conform to standard brick bonds, and which can easily be discerned as imitation of brickwork.

An object of the present invention is to provide a multiple brick unit with straight edges which may be joined to one another, end to end, 40 without the joints being visible except by very close scrutiny. The invention may be adapted to all types of brick from the multiple unit solid brick or building block to the imitation asbestos or asphalt covered wallboard or facing sheets 45 where bricks are simulated by the use of granules, grits, or brick dust. The invention is preferably adapted to the thin tile type of brick which is pressed on to a stiff wallboard backing which has been coated with a suitable bonding material.

A further object of the invention is to provide a backing board which is especially adapted for use with the thin brick or tile slabs. This backing board comprises a stiff sheet having 55 raised portions extending longitudinally and spaced to include the width of the half slabs. These raised portions permit rapid and economical assembly, for example, of a prefabricated multiple brick unit and they also furnish rigidity to 60

the completed brick facing sheet. They also tend to hold the slabs in place during the period the cement is setting, and allow for positive and quick alignment of the courses. They also tend to hold the slabs from the possibility of sliding down were the cement to give way.

More specifically it is the object of the invention to utilize a half length brick or tile which is provided with a surface configuration which blends into an adjoining half brick in such manner that the joint is practically imperceptible.

The following drawings and description disclose various modifications of the invention hereinafter claimed.

Fig. 1 is a perspective view of the preferred form of brick to be used in my novel multiple unit.

Fig. 2 illustrates the manner in which these bricks are placed end to end forming a brick facing similar to that of the standard brick.

Fig. 3 is a side elevation of the preferred form of brick facing unit.

Figs. 4, 5 and 6 illustrate modifications in the configuration of the facing of the brick.

Fig. 7 illustrates the manner in which the brick units disclosed in the preceding figures are mounted on rectangular backing members and the manner in which the individual backing members joint at the ends.

Figs. 8 and 9 illustrate the modifications in which the brick units of the facing sheet are formed by granules pressed into the bonding material.

Figs. 10 and 11 illustrate the preferred type of backing member to be used with my novel brick.

Figs. 12 and 13 illustrate cross sections of prefabricated building panels made up partly of facing sheets disclosed in the previous figures.

Fig. 14 is a cross section of the brick facing sheet shown in Fig. 7.

Fig. 15 illustrates the manner in which the invention may be adapted to building blocks having one side faced to simulate brick.

Fig. 16 illustrates the dimensional relationship between the studs of the building and the brick facing units.

Fig. 17 illustrates the manner in which the brick slabs illustrated in Figs. 1 to 7 can be stacked in the firing and drying kilns.

One of the main features of the present invention resides in the specific configuration of the facing of the brick units shown in the drawings. Relatively thin tiles or brick slabs have been used prior to this invention for the forming of ornamental facing sheets to be used in the construction of houses and other buildings. The present invention, in its preferred embodiment, proposes to form the bricks or briquettes which are used in these facing sheets, of small

clay slabs or clay particles such as that shown in Figs. 1, 4, 5 and 6. These slabs are comparatively thin if compared with the standard brick but have a width which is substantially equal to the width of the ornamental face of a standard brick and a length which is substantially equal to one-half the length of the standard brick. The preferred thickness is $\frac{1}{4}$ inch. It is preferred that these half slabs be $2\frac{1}{4}$ inches wide and about $3\frac{3}{4}$ inches long so that the combined 10 brick, as that shown in Fig. 2, will have a length of $7\frac{1}{2}$ inches. When used with a $\frac{1}{2}$ inch mortar joint the module for each brick and its joint will be 8 inches, or 4 inches for each half brick and its proportionate joint. The reason for this 15 maintenance of an 8 inch module for the full brick and one mortar joint is to allow the spanning of studs which are spaced at 16 inches in standard practice of wall construction. The multiple sheets which are composed of courses of these brick units can be any multiple of 16 inches in length. The use of the 4 inch half brick modules will also allow the making of multiple sheets to any multiple length of 4 inches and this makes them especially useful in the building of prefabricated sectional wall units which are being used today in increasing amounts in the construction of prefabricated houses. I do not wish to be entirely limited to this size, as other dimensions can be used, as long as the brick, composed of the two 20 end to end slabs, appears to have a face size comparable to a brick and which can be discerned as of brick size, even though the 8 inch module is not obtained in every brick.

Another reason for the novel dimensions of the half bricks and the method of using two tiles or slabs together to simulate one full brick is that in burning the clay in production, the shorter the piece is, the less trouble is encountered with warpage or distortion especially with the lower cost shales. In making these tiles in two 25 separate pieces the length is cut down and there is a negligible loss in the drying and burning of the smaller slabs as compared with the comparatively high loss in the burning of the slabs which are substantially the length of the ordinary brick. Furthermore, the pressure which is necessary to press the slabs onto the backing member to form the completed unit, tends to crack a long thin slab which is warped to any degree, whereas, when applied to the face of the smaller slabs, it will be less apt to crack them.

A further important reason for the use of the two half bricks, or the splitting feature of the length of the individual brick into two equal parts, is to allow for the manufacture of a square edge multiple brick unit which will maintain a so-called continuous or unbroken bond in each brick course when the multiple brick units are placed end to end.

The illusion of a continuous bond is brought about by a configuration on the outside face of the half bricks which allows the building of each half brick into an adjoining half brick in such manner that the joint is very difficult to discern. With the use of a half brick, a much thinner slab can be made with great saving in material since a full size slab of approximately $\frac{1}{4}$ inch thickness cannot be manufactured without considerable loss in burning.

One modification of the invention is shown in Fig. 1, where the facing of the tile 20 is provided with a number of vertical scratches, furrows, or cuts 21, and the outside end 22 of the face of the tiles left plain. When the tile 20 is placed end to end with a similar tile 23, Fig. 2, the appear-

ance is that of a solid brick. A joint 24 between the tiles 23 is blended into the vertical grooves or cuts 21 so that it appears as one of them. The two plain margins 22 of the brick serve to carry out the illusion of a full brick since the ends are dissimilar to the center. If desired the brick face may be plain except for the portion adjacent the joining ends of the slabs.

Other texturing can be superimposed on the vertical texturing, or textured first, to make further desired designs, Fig. 4, although in my preferred method I use a comparatively straight vertical texturing to better conceal the vertical joint 24. It is also possible to provide other designs in the face of the brick which will serve equally well to hide the center joint. For example, in Fig. 5, a series of S-like scratches 25 are formed in the surface of the brick, these scratches having substantially vertical portions which blend in with the vertical joint. A further modification in Fig. 6 shows that the joining end 26 between the bricks may be a wavy or zigzag line, and when the surface of the bricks is also provided with wavy or zigzag scratches 27 the joint between abutting bricks is again practically concealed. An advantage in forming substantially continuous grooves in the face of the slabs lies in the fact that the slabs may be stacked during drying and burning (see Fig. 17), thereby affording an economy of manufacture. The 30 grooves carry the air and heat through the layers without the necessity of further separation. Another possible design is the use of half bricks having a joining end at an angle with the top and bottom edges and having grooves in the ornamental face which are parallel with the joining end. I do not propose to limit myself to a brick face which is provided throughout with grooves or scratches as long as the portion of the face adjacent the joining ends of the slabs is provided with grooves having a configuration substantially similar to the configuration of the joining end.

A cross section of the facing sheet illustrated in Fig. 7 is shown in Fig. 14. A relatively stiff 35 backing member 28 is covered with an asphalt or other bonding material which is applied while still soft and the slabs are held firmly in position. The bonding material will tend to squeeze up between the brick slabs in the mortar lines as at 30 and will create the appearance of mortar between the bricks. If desired these mortar cracks can be pointed in with mortar or other material having the appearance of mortar or grits or other material can be placed into or on top of the bonding material and adhered to same. However, one reason for using the thin slab of approximately $\frac{1}{4}$ inch thickness is that the slabs need not be mortared after they are applied.

The preferred type of backing for the half 40 bricks is illustrated in Fig. 10 where it will be seen that a backing member 31 is provided with horizontal raised portions 32, which are approximately the width of the mortar joint and which are spaced apart at a distance equal to the width of one brick. The half bricks are pressed into place between the raised portions 32 on the backing 31, after a suitable bonding material has been applied to the backing 31. The bricks will be spaced as at 33 and this space filled with a mortar or some other substance having the same appearance. This backing sheet is shown in cross section in Fig. 11.

In both the modifications shown in Figs. 7 and 10 it is preferable that the half bricks on 45 the end of the facing sheet extend exactly to the

edge of the facing sheet, or slightly over the edge, and that the whole bricks which are located at the ends of the sheet be spaced one-half of a mortar joint from the end of a sheet. In this way the abutting ends of the various facing sheets can be placed together to form a continuous bond. For example, referring to Fig. 7, the back sheets 34 and 34a are shown spaced slightly apart from each other. When they are placed end to end the two half bricks 35 and 36 on each facing sheet will join together to form whole bricks, and the half mortar joints 37 will join together to form a whole mortar joint similar to 38. The facing sheet shown in Fig. 10 is especially adapted for use in forming prefabricated panels in one piece which will form a completed wall of inside and outside finish. In Fig. 13, for example, a facing sheet 39 is connected by studs or structural members 40 to an inner panel 41. On the other hand the panel 34 shown in Figs. 7 and 14 can also be used for this purpose and a cross section of a prefabricated panel using the facing sheet 34 is shown in Fig. 12.

As stated above it is desirable that the completed dimensions of the face brick shown, for example, in Fig. 2, be substantially similar to the exposed surface of a standard brick, but it was also stated that the preferred module for each brick with one mortar joint is 8 inches. The importance of this is well illustrated in Fig. 16 where studs 42 are located 16 inches apart from center to center. The 16 inch dimension being a standard spacing for building studs. It will be noticed that the mortar joints of every other brick course fall directly over the studs so that nails 43 could be driven into the studs through these mortar joints to hold the facing sheets in position.

A modification of the invention is shown in Figs. 8 and 9 where a stiff backing member 44 is covered with an asphalt or asbestos 44a substance into which mortar grooves 45 have been pressed. The asbestos is covered with granules 46 formed of ground pebbles, slate, brick, or sand or other materials which are pressed into the asphalt or other adhesive. Bricks can also be simulated simply by coloring the various raised portions on the asphalt 44a. In accordance with the invention the half bricks 47 are pressed so as to form a number of vertical lines 48 which will serve to conceal the joint between the half bricks 47 and other half bricks of an adjoining facing sheet. It is not necessary that all the bricks in the facing sheet, shown in Fig. 8, be provided with vertical lines though it is sometimes desirable that certain bricks in each course be textured in the same manner as the half bricks at the end of the facing sheet in order to provide a symmetry of design.

A further modification of the invention is shown in Fig. 15 where a building block 49 has one surface which is formed to create the appearance of a brick wall. This may be accomplished by forming mortar grooves in the block itself or by fastening prefabricated tile slabs directly on to the face of the block. For example, the block 49 contains four whole bricks and four half bricks. In order to create the appearance of a continuous bond in a wall made up of blocks 49, the half bricks or all of the bricks are textured with vertical lines or other types of lines

as above described so that the joints between the half bricks of block 49 and the half bricks of the adjoining block will be imperceptible except upon close examination.

It will be seen from the above description that the invention can be adapted to most any type of actual brick or imitation brick facing material.

The word "groove" as used in the specifications and claims in connection with brick surfaces shall be understood to mean cuts, furrows, or scratches in the brick surface formed by rolling or scratching tools.

I claim:

1. An exterior multiple brick unit adapted to be secured to the base wall of a building comprising a rigid backing member and a plurality of relatively thin ornamental tile slabs directly secured thereto and placed end to end in pairs in such manner that each pair of slabs has an exposed surface of substantially the same dimensions as a standard brick, the surface of said slabs being textured to simulate a brick surface.

2. An exterior building unit adapted to be secured to the base wall of a building for forming part of an ornamental veneer wall, comprising a rigid backing member and a plurality of relatively thin ornamental slabs directly secured thereto and placed end to end in pairs in such manner that each pair of slabs has an exposed surface of substantially the same dimensions as the exposed surface of a standard brick, said slabs having the outer surface thereof textured with grooves to simulate the joint in each pair of slabs, and said pairs of slabs being spaced apart to simulate brick courses having a continuous bond.

3. An exterior multiple brick unit adapted to form a part of an ornamental veneer wall, comprising the combination of a rectangular comparatively stiff backing member and a plurality of relatively thin ornamental brick slabs covering said backing in pairs and single units to simulate a rectangular section of a standard brick wall having an unbroken bond, said slabs being spaced to simulate mortar lines, the single slabs being located at each end of said backing and adapted to abut similar slabs in an adjoining backing member, said slabs having surface configurations substantially transverse thereof.

4. A multiple brick facing sheet adapted to form a portion of a simulated brick wall, comprising a relatively stiff four sided backing member, longitudinally extending raised portions on said backing member spaced substantially as are horizontal mortar spaces in a standard brick wall, and a series of relatively thin half bricks arranged in pairs between said raised portions to simulate horizontal brick courses.

5. A brick slab for use in pairs to simulate a brick surface comprising a rectangular comparatively thin brick approximately half the length of a standard brick and having a finished end and a joining end, said brick slab having a portion of one surface adjacent the joining end provided with closely spaced substantially transverse furrows corresponding in configuration to the joining end of said slab, the remaining portion of said surface, consisting of a margin adjacent the finished end, being relatively smooth.

NATHANIEL L. ABERSON.
